UNITED STATES PATENT OFFICE.

MARCUS RUTHENBURG, OF HARRISBURG, PENNSYLVANIA.

ART OF MAKING BLEACHING COMPOUND.

SPECIFICATION forming part of Letters Patent No. 739,448, dated September 22, 1903.

Application filed January 14, 1902. Serial No. 89,744. (No specimens.)

To all whom it may concern:

Be it known that I, MARCUS RUTHENBURG, of Harrisburg, in the State of Pennsylvania, have invented certain new and useful Improvements in Bleaching Compounds and in the Art of Making the Same, whereof the following is a specification.

My invention relates to aqueous solutions of chemicals adapted for bleaching cellular substances, such as paper-pulp and the like; and it is the object of my invention to obtain the maximum bleaching effect from a given quantity of chemical employed.

The process of making my improved compound consists in mixing, in definite proportions, an aqueous solution of sodium chlorid with an aqueous solution of hydrated oxid of calcium and subjecting the mixture to the action of an electric current until the product is a compound having the peculiar characteristics hereinafter specified and comprising a double chlorin salt of sodium and calcium.

In the conduct of my process aforesaid I have found it convenient to employ an aqueous solution comprising twenty per cent. of sodium chlorid, mixed with an aqueous solution containing ten per cent. of hydrated oxid of calcium and to subject the mixed solution to the action of an electric current from electrodes supplied with current in the proportion of one-half ampere per square inch of the electrode-surface exposed to the solution and at a pressure of three volts until the chemical components of the mixture are reduced to the state of hypochlorites, which condition may be ascertained by the usual arsenious-acid test.

I am aware that it has been hitherto known that a bleaching agent may be produced by electrolyzing a solution of sodium chlorid *per se*. However, one effect of such electrolysis is to liberate a large percentage of chlorin from the solution, with consequent loss of bleaching efficiency of the latter.

My present invention is advantageous in that the production of a bleaching agent from the sodium chlorid is effected by the electrolysis without dissipating the chlorin as heretofore, the chlorin being taken up by the hydrated oxid of calcium, forming additional soluble chlorin salt in the solution,

and thus augmenting the bleaching capacity of the latter. It is also to be noted that the addition of the oxid of lime to the solution increases the conductivity of the latter, and thus effects a considerable saving in the amount of the electric current employed to effect the electrolysis.

Although I prefer to employ the oxid of calcium because of its low cost, it is to be noted that an equivalent effect may be produced in the solution by the addition of the oxides of magnesium, lithium, aluminium, sodium, and potassium.

It is to be noted that the electrolyzed compound produced by the process herein set forth is characterized by greater bleaching efficiency than a mere mixture of hypochlorites of sodium and calcium of equivalent oxidizing capacity—that is to say, of two compounds whose oxidizing capacity is determined to be equal (by the arsenious-acid test) the electrolyzed compound manifests greater bleaching efficiency, is more rapid in its effects, and for a given degree of whiteness obtained the electrolyzed compound detracts less from the weight of the material treated. It is also to be noted that although my improved compound is weakened in bleaching effect by continued use it may be restored to its initial efficiency by the addition of suitable proportions of the chemicals aforesaid and renewed subjection to the action of the electric current.

In view of the variable nature of the chemicals named I do not desire to limit myself to the employment of the particular percentages thereof above specified. It is also to be understood that the desired electrolysis of the mixture may be effected by more or less exposure to an electric current of dimensions differing from those above specified.

I claim—

1. The hereinbefore-described process of making a bleaching compound, which consists in making an aqueous solution comprising twenty per cent. of sodium chlorid; mixing with said solution an aqueous solution containing ten per cent. of hydrated oxid of calcium; subjecting the mixed solution in a free state to the action of an electric current supplied in the proportion of one-half ampere per square inch of the electrode-surface, exposed

to the solution, and at a pressure of three volts, until the chemical components of the mixture are reduced to the state of hypochlorites, substantially as set forth.

- 5 2. The hereinbefore-described process of making a bleaching compound, which consists in making an aqueous solution comprising twenty per cent. of sodium chlorid; mixing with said solution an aqueous solution containing a less percentage of the oxid of an alkaline; subjecting the mixed solution in a free state to the action of an electric current supplied in the proportion of one-half ampere per

square inch of the electrode-surface, exposed to the solution and at a pressure of three volts 15 until the chemical components of the mixture are reduced to the state of hypochlorites, substantially as set forth.

In testimony whereof I have hereunto signed my name, at Philadelphia, in the State 20 of Pennsylvania, this 13th day of January, 1902.

MARCUS RUTHENBURG.
